Primary Examiner — Eric Goodman*Assistant Examiner* — Daniel J Domino*(74) Attorney, Agent, or Firm* — Ralph Dougherty(57) **CLAIM**

The ornamental design for a flexible bushing, as shown and described.

DESCRIPTION

FIG. 1 is a perspective view of a flexible bushing showing our new design;

FIG. 2 is a bottom view thereof;

FIG. 3 is a front view thereof;

FIG. 4 is a top view thereof;

FIG. 5 is a rear view thereof.

FIG. 6 is a left end thereof; and,

FIG. 7 is a right end view thereof.

The flexible bushing is shown with a symbolic break in its length. The appearance of any portion of the bushing between the break lines forms no part of the claimed design.
